United States Patent Office

Des. 213,881
Patented Apr. 22, 1969

213,881

BADGE

Donald Librande, 98 Hazard Road,
Carpentersville, Ill. 60110

Filed July 30, 1968, Ser. No. 12,959

Term of patent 14 years

Int. Cl. D11—03

U.S. Cl. D29—6

FIG. 1.

FIG. 2.

FIG. 3.

FIG. 4.

The dominant feature of the design is shown in full lines.

I claim:

The ornamental design for a badge, substantially as shown and described.
